CLAIM

The ornamental design for a blow molded wheel, as
shown and described.

DESCRIPTION

FIG. 1 is an isometric view of a blow molded wheel
showing our new design;

FIG. 2 is a front elevation view thereof, the rear being
a mirror image of that shown;

FIG. 3 is a side elevation view thereof; and,

FIG. 4 is a cross sectional view thereof taken along lines
4—4 of FIG. 2.

FIG. 1

FIG. 2

FIG. 4

FIG. 3
